UNITED STATES PATENT OFFICE

JOHN J. HOEY, OF PROVIDENCE, RHODE ISLAND

TENTER CLIP

Application filed May 22, 1928. Serial No. 279,786.

This invention relates to tenter clips and particularly to the mounting of the work engaging blades carried by the swinging jaws of tenter clips.

5 An object of the invention is to provide a tenter clip wherein the swinging jaw has a reversible work engaging blade.

Another object is to provide a tenter clip wherein the work engaging blade of the 10 swinging jaw has opposite working surfaces.

Another object is to produce an efficient, strong and durable tenter clip which may be economically constructed and operated.

With these and other objects in view, the 15 invention consists of certain novel features of construction, as will be more fully described, and particularly pointed out in the appended claims.

In the accompanying drawings:—

20 Figure 1 is a vertical transverse section through a tenter clip constructed according to the invention;

Figure 2 is a vertical section taken on the line 2—2 of Figure 1;

25 Figure 3 is a detail section as seen from the line 3—3 of Figure 2;

Figure 4 is a similar view taken approximately on the line 4—4 of Figure 2;

30 Figure 5, 6 and 7 are perspective views of parts of the swinging jaw; and

Figure 8 shows the jaw member as formed in one piece and slotted to receive the blade also showing a separate clamp for retaining the blade.

35 Owing to the present day practice of rapid travel required of the chain in tentering machines, the constant severe banging or hammering action in opening and closing the swinging clip jaws to engage and release the

40 work dulls the biting edges of the blades of the jaws, thereby necessitating frequent removal of the blades for resharpening or replacement. Therefore, to obviate this difficulty to a great extent, I have provided the 45 swinging jaw with means for retaining a reversible blade having opposite working edges.

The construction also includes means whereby the blades can be quickly removed from the jaws, reversed and reset, and means for 50 enabling the blades to be properly positioned

so as to reduce the time required to install the blades in the jaws; and the following is a detailed description of the present embodiment of this invention and showing means by which these advantageous results may be accomplished:—

55 Referring to the drawings, the tenter clip has the usual fixed jaw 11, and a swinging jaw 12. The jaw 12 is pivotally mounted on a pin 13 carried by the upper overhanging portion 60 of the clip.

The jaw 12 is controlled in its swinging action by a controller or feeler member 14, which may be delicately pivoted on a small pin 15 in a bracket 16 projecting rearwardly 65 from a plate 17 carried by the jaw 12.

The purpose of the swinging jaw 12 is to grip the work (not shown) carried by a plate 18 on the fixed jaw 11, and in order to provide a wear surface for the swinging jaw I form a 70 separate hardened steel blade 19 in the lower horizontal edge of this jaw.

In the present instance, the blade is reversible and has opposed beveled edges 20 formed longitudinally thereof, the blade being 75 removably disposed in a slot 21 formed between the plate 17 and the lower portion 22 of the jaw 12.

For the purpose of enabling the plate to be quickly detached from or affixed to the jaw, 80 the plate has threaded openings 23 formed near each end thereof for receiving the screws 24 passed thru openings 25 in the jaw 12, the openings 23 being aligned with the openings 25 by means of pins 26 carried by the jaw 12 85 seating in correspondingly disposed openings 27 formed in the plate 17.

90 Preferably the blade 19 should be slightly thicker than the width of the slot 21 so that when the screws 24 are set up the plate 17 will be drawn towards the portion 22 of the jaw to clamp the blade in position.

A pin 28 is carried by the portion 22 of the 95 jaw 12. This pin is transversely disposed, and it is adapted, when the parts are being assembled to project into an opening 29 formed in the plate 19. The pin should be so disposed in the jaw that it will engage with a notch 30 formed in the edges of the blade 20, as clearly shown in Figure 2, to center the 100

same endways in the slot and also form a support on which the blade may rock while being set.

When it is necessary to provide a new gripping edge for the swinging jaw 12, the blade 19 can be easily removed by loosening the screws 24 to permit a slight separation of the plate from the jaw whereupon the blade can be reversed edge for edge and reinserted within the slot 21 with the notch 30 in registration with the pin 28. The jaw 12 can now be moved to the position shown by Figure 1 so as to permit the blade 19 to rock on its backing pin 30 and be properly seated in alignment with the jaw 11 while such blade is loosely mounted in the jaw 12. When the blade has been reset to the desired position, the screws 24 are tightened and the device is now ready for operation.

20 In some instances, the two parts of the jaws 12 and 17 may be cast integral and slotted at its lower edge to receive the blade 19 which may be fitted into this slot and retained therein by separate clamps 31 shown in Fig. 8.

25 The foregoing description is directed solely towards the construction illustrated, but I desire it to be understood that I reserve the privilege of resorting to all the mechanical changes to which the device is susceptible, the invention being defined and limited only by the terms of the appended claims.

The invention claimed is:—

1. In a tenter clip a jaw member, a reversible blade cooperating means on said jaw member and blade for aligning said blade on reversal thereof, and means for clamping said blade to said jaw member.

2. In a tenter clip a swinging jaw, a reversible hardened blade having two opposite work engaging edges, cooperating means on said jaw and blade for aligning said blade in either of its working positions, and means for securing the aligned blade to the jaw.

3. In a tentering clip, the combination with a jaw having a slot formed therein, of a reversible blade, means carried by the jaw for aligning the blade in either working position, and means for securing the aligned blade in the slot.

50 4. In a tentering clip, the combination with a jaw having a slot formed therein, of a notched blade detachably mounted within the said slot, means for clamping the blade to the jaw, and means carried by the jaw for engaging the notch in the blade to align the blade and prevent dislodgment thereof from the jaw.

55 5. In a tentering clip, the combination with a jaw having a slot formed therein, a detachable plate covering the slot, means for aligning said plate with the said jaw, a reversible notched blade mounted within the said slot and clamped to the jaw by the said plate, and means carried by the jaw for engaging the notch in the blade.

6. In a tenter clip a fixed jaw, a swinging jaw having a slot, a central backing abutment in the slot, a reversible blade having opposite working edges and mounted in the slot, one of said edges engaging said central abutment on which the blade may rock to align itself with the fixed jaw, and means for clamping the blade in the slot.

In testimony whereof I affix my signature.

JOHN J. HOEY.
